UNITED STATES PATENT OFFICE

ALPH. M. LICKLEY, OF EAST CLEVELAND, OHIO, ASSIGNOR, BY MESNE ASSIGNMENTS, TO THE TALMAGE MANUFACTURING COMPANY, OF CLEVELAND, OHIO, A CORPORATION OF OHIO.

LOCOMOTIVE DRIFTING DEVICE

1,275,055.

Specification of Letters Patent. Patented Aug. 6, 1918.

Application filed February 9, 1915. Serial No. 7,182.

To all whom it may concern:

Be it known that I, RALPH M. LICKLEY, a citizen of the United States, residing at East Cleveland, in the county of Cuyahoga and State of Ohio, have invented a certain new and useful Improvement in Locomotive Drifting Devices, of which the following is a full, clear, and exact description, reference being had to the accompanying drawings.

The object of this invention is to provide a very simple and efficient equipment for a locomotive adapted to cause small quantities of steam to enter the cylinders automatically when the throttle is closed. Such admission of steam prevents grit and products of combustion being drawn back from the stack onto the valve seat and into the cylinder when the locomotive is drifting, (i. e., running by momentum or gravity), thus obviating the abrasion of the valve seat and cylinder and the carbonization of the lubricant otherwise liable to occur. My system admits the live steam, not only when the locomotive is drifting, but when it is standing, so that the discharging steam acts as a blower to maintain the draft, and also serves to keep the cylinders warm, reducing the condensation when the locomotive is again started.

30 I accomplish the above results by providing a system of pipes for conveying steam to the cylinders, and an automatic valve controlling the passage through such pipe and itself controlled by the pressure conditions in the valve chest through a pipe connecting the automatic valve therewith. My automatic valve operates upon reduction in steam pressure in the valve chest following the closing of the throttle, but before such 40 steam pressure is reduced to atmospheric pressure. This steam of reduced pressure entering the cylinder through the distributing valve ports, there is never a vacuum, or partial vacuum, in either the valve chest or cylinder, and no tendency for the products of combustion to be drawn into the cylinder. My invention is hereinafter more fully explained in connection with an illustrative embodiment thereof, and the essential characteristics are summarized in the 50 claim.

In the drawings, Figure 1 is a side elevation and Fig. 2 is a plan of my equipment mounted on a typical locomotive; Fig. 3

is a longitudinal central section of my controlling valve; Fig. 4 is a plan of half of such valve; Fig. 5 is a vertical cross section of the same half of the valve on the line indicated by 5-5 on Fig. 3; Fig. 6 is a vertical section of piping and check valves connecting the forward portion of my steam delivery pipe with both ends of the cylinder.

Referring first to the broken lines in Figs. 1 and 2, A designates the steam space of the locomotive, B the usual turret connected therewith, C the cylinder, D the valve chest, E the dry pipe and F the throttle.

In Figs. 1 and 2, my attachments are shown in solid lines. 10 designates the casing of my automatic valve, the interior of which is connected by a pipe 11 with the supply of live steam. As shown, this connection is to the turret B through a suitable normally open shut-off valve 13. Extending 75 from the casing 10 are two pipes 15 which lead to suitable points in the two cylinders of the locomotive. The connection may be variously made to the cylinder, as desired, but I prefer to connect the forward end of the pipe 15 by a T with pipes 16 leading to the two ends of the cylinder. 17 indicates a pipe leading from one of the valve chests or from the dry pipe of the locomotive back to the valve casing 10.

I will now describe the movable member within the casing 10 which operates under the influence of the pressure conditions in the pipe 17 to connect the pipe 11 with the pipes 15, or to interrupt communication between them. This movable valve member may be of any suitable form adapted to accomplish the result, which is to establish communication between the pipes 11 and 15 when the steam pressure in the pipe 17 drops below a predetermined minimum (which is still above atmospheric pressure), and to shut off such communication when the valve chest pressure rises above that minimum.

A simple way to accomplish the desired movement of the movable valve member is to oppose the valve-chest-pressure acting to move the valve member in one direction by a spring tending to move in the other direction. This is the construction shown in Fig. 3, where 20 indicates the movable valve member shown as provided with three

21 pistons 21, 22 and 23, and given a tendency to move toward the right by a helical compression spring 25. The intermediate piston 22 acts as a valve plug controlling the exit 5 ports 40 to the pipe 15. For convenience of construction the three pistons are formed on a single central stem 27, while on the outer sides of the pistons 21 and 23 are extensions of the stem or bosses 28 and 29. 10 Each of these bosses, by abutting an inward boss 30 or 31 on the end caps 32 or 33, limits the movement of the valve member. The bosses 28 and 30 also act to position the spring 25. 15 By making the piston member of the symmetrical form shown so that it may be inserted in the casing, either end foremost, and by making the end caps duplicates of each other, I simplify and cheapen the construction and reduce the chance of any error in assemblage. If it be desired to increase the force of the spring 25, it is only necessary to place one or more washers about the boss 30 between the spring and 25 cap 32.

The pipe 11 from the live steam supply is connected by a union 35 with an extension 36 of the casing 10, and is in open communication with the interior and conveys live 30 steam in all positions of the piston valve between the pistons 21 and 22. These pistons being of the same size, the pressure is balanced and the live steam gives the pistons no tendency to move. Fig. 3 shows the 35 position of the pistons when the throttle is closed; that is, while the locomotive is drifting or standing. During such periods there is a minimum of pressure in the valve chest and the force of the spring 25 pushes the 40 pistons to the right, as shown in that figure, as hereinafter more fully explained.

When the engine is running there is necessarily steam pressure in the pipe 17 because it is directly connected with the valve 45 chest or dry pipe, and this pressure, acting on the piston 23, forces it to the left against the action of the spring 25, thus carrying the piston 22 to the left of the exit ports 40 in the wall of the valve chamber and confining 50 the live steam. Accordingly, during the running of the engine, my controlling valve is out of action.

Whenever the throttle is closed, such action causes immediate diminution of steam 55 pressure in the valve chest and cylinder, which pressure, in the old operation, drops below the atmospheric pressure and causes the troublesome inrush from the stack. With my construction, however, as soon as 60 the steam pressure in the valve chest has dropped to a certain minimum, for example,—to a few pounds above the atmosphere, the spring 25 being no longer opposed by a corresponding pressure against the piston 23, moves the pistons to the right into

the position shown in Fig. 3, and this admits live steam from the pipe 11 through the ports 40 into the annular passageway 41 which is connected by unions 42 with the pipes 15 leading to the cylinders. 70

Such admission of live steam prevents any vacuum being formed in the cylinders, and, as this steam is discharged through the valve chest and into the stack it acts as a blower for the fire, and it serves to maintain the cylinder hot. Whenever the throttle is open again, the pressure in the pipe 19 immediately counter-balances the spring 25 and forces the piston to the left, shutting off communication to the pipes 15. 80

Any leakage of steam past the piston 21 is carried away by the drip pipe 45 leading to the atmosphere. Any leakage of steam from the pipe 11 past the piston 22 or from the pipe 17 past the piston 23 into the space 85 between these pistons has no tendency to move the piston structure, and is immaterial.

The simple automatic valve shown, it will be seen, provides the desired steam admission to the cylinder whenever the throttle is closed, doing away with the evils of suction into the cylinder and valve chest while drifting, and providing heat and blowing action while standing. There is no tendency 95 whatever of the locomotive to start into motion by reason of an accumulation of steam pressure in the cylinders while standing, because the steam is admitted directly to the cylinder on both sides of the piston 100 and not to the valve chest—admission at the latter point being dangerous, as it may accumulate sufficiently to drive the engine.

Since to connect the pipe 15 directly to the center of the cylinder would allow the formation of some vacuum in the end of the cylinder until the piston has moved past the middle of its stroke and opened the central admission point, I prefer to connect the pipes 15 with the two ends of the cylinder. When 110 so connected, I provide check valves preventing circulation of steam from one end of the cylinder to the other when the locomotive is being driven.

Fig. 6 shows a convenient system of piping and check valves to the two ends of the cylinder. In this case the pipe 15 is connected by a T 53 with two pipes 16, which are connected by unions 50 with elbows 51, which are tapped at 52 into the cylinder wall 120 adjacent to its ends. Within each elbow is a chamber occupied by a ball 54, which is adapted to be seated by the cylinder pressure against a seat 56 on the entrance portion of the elbow. In ordinary running, the 125 pipe 15 is closed and one or the other of the balls 54 is held against its seat by pressure in the corresponding end of the cylinder, so that circulation from one end of the cylinder to the other is prevented. When drifting, 130

- however, the pressure in the pipes 15 and 16 forces the balls 54 away from their seats and feeds the two ends of the cylinder, as desired. This same admission of steam may 5 continue after the engine has come to a stand-still and may be advantageous in maintaining the cylinders hot, or it may be shut off at the cab to save steam. Even if continued indefinitely, it would not operate to 10 start the locomotive, for one side of the piston is usually open to the exhaust. This will furnish a vent for the additional steam, relieving it as fast as it is supplied, and no pressure will build up at the cylinders. 15 Should the distributing valve happen to be in a position where both ends of the cylinder are closed to the exhaust, then the additional steam will pass to both sides of the piston and be balanced.
- 20 To conveniently assemble the ball checks described, as well as allow the valve seats to be reground, when desired, I make a threaded opening opposite the valve seat, into which are screwed suitable closure plugs 57, each formed with an inwardly extending boss 58, normally forming a stop for the ball. Suitable wings 59 carried by the wall of the elbow properly guide the ball.

Having thus described my invention, what I claim is:

In a locomotive drifting device, the combination of a boiler, a dry pipe leading therefrom, a throttle controlling admission to the dry pipe, a steam chest with which the dry pipe communicates, a distributing valve in 35 the steam chest, a cylinder adapted to be in communication with the steam chest under the control of said distributing valve, a conduit leading from the boiler independently of the throttle and leading by branches directly to both ends of the cylinder independently of the distributing valve, check valves in said branches preventing by-passing from one end of the cylinder to the other, an automatic valve in said conduit between the check 40 valves and boiler, said automatic valve having constantly acting means tending to open it and having a pressure-responsive device in communication with the steam chest adapted to close it.

In testimony whereof, I hereunto affix my signature in the presence of two witnesses.

RALPH M. LICKLEY.
